ATTYS.

UNITED STATES PATENT OFFICE.

JAMES REICHENBERG, OF LONDON, ENGLAND.

DESIGN FOR A WATCHCASE.

Application filed May 28, 1924. Serial No. 9,732. Term of patent 7 years.

To all whom it may concern:

Be it known that I, JAMES REICHENBERG, a subject of the King of England, residing at 7 Hatton Garden, London, England, have invented a new, original, and ornamental Design for a Watchcase, of which the following is a specification, reference being had to the accompanying drawing, forming part thereof.

The figures are respectively a front and side view of the watch case illustrating my new design.

I claim:

The ornamental design for a watchcase, as shown.

JAMES REICHENBERG.

Witnesses:

LOUIS H. MONBY,
WILLIAM WARDEN.
